UNITED STATES PATENT OFFICE.

JOHN ZIMMERLI, OF PROVIDENCE, RHODE ISLAND.

FLYING-MACHINE.

992,099.

Specification of Letters Patent.

Patented May 9, 1911.

Application filed April 23, 1910. Serial No. 557,124.

To all whom it may concern:

Be it known that I, JOHN ZIMMERLI, a citizen of the Republic of Switzerland, residing at Providence, in the county of Providence and State of Rhode Island, have invented new and useful Improvements in Flying-Machines, of which the following is a specification.

This invention relates to flying machines, and particularly to a flying machine of the combined helicopter and aeroplane type.

The primary object of the invention is to provide a flying machine in which a series of propellers and air-planes are used which 15 may be adjusted at the will of the aviator to different angles for securing a free ascent or descent of the machine and for propelling the machine forward at a considerable rate of speed and controlling and steadyng the 20 machine in its flight.

A further object of the invention is to provide a novel construction and arrangement of air-planes whereby the supporting surfaces are properly distributed and 25 greater stability obtained, and also to provide a construction and arrangement of rudders or steering planes which in operation will not only guide but properly tip or incline the machine in making a turn so as to 30 secure an ease of motion in steering while preserving the balance of the machine.

With these and other objects in view, the invention consists of the features of construction, combination and arrangement of 35 parts hereinafter fully described and claimed, reference being had to the accompanying drawings, in which:

Figure 1 is a side elevation of a flying machine embodying my invention. Fig. 2 is 40 a vertical longitudinal section through the central portion thereof. Fig. 3 is a vertical cross section on line 3—3 of Fig. 2. Fig. 4 is a top plan view of a portion of the machine. Fig. 5 is a front elevation. Fig. 6 is 45 a detail view showing the construction of the propeller gearing.

Referring to the drawings, the numeral 1 designates the frame of the machine which may be of any suitable construction and provided, if desired, with supporting wheels 2 for convenience in transporting the same from place to place along the ground. Mounted upon the frame are sets or series of forward, intermediate and rear planes ar- 55 ranged in tandem and in transverse aline-

ment on opposite sides of the center of the machine. Each set of planes comprises an upper plane 3 and a lower plane 4, the lower plane being arranged close to the frame of the machine, while the upper plane is arranged at a desired elevation above the same and is of larger area than said lower plane to correspondingly increase the supporting surface at the top of the machine. By the arrangement shown, a triple bi-plane 60 machine is produced, but the number of plane divisions employed may be varied as desired.

Each upper plane 3 is carried by a shaft 5 journaled in bearings upon standards or 70 brackets 6 rising from the frame, which shaft is provided with oppositely projecting lever arms 7 and 8, while each lower plane 4 is mounted upon a shaft 9 journaled in bearings 10 on the frame, which shaft is 75 similarly provided with oppositely extending lever arms 11 and 12. The upper and lower planes of each set are adapted to be adjusted or moved in unison from a horizontal to a vertical position or to any intermediate angle, through the medium of an operating lever 13 and suitable connections. As shown, a cord or cable 14 is connected with the lever below its pivot, passes over suitable guide pulleys 15 on the frame and 80 is directly connected with the lever arms 8 and 12 of the upper and lower planes of the front and rear sets and is connected by a branch cable 16 with the corresponding lever arm of the planes of the intermediate 85 set. A second cord or cable 17 is connected with the lever 13 above its pivot point, passes around guide pulleys 18 on the frame and is connected with the lever arms 7 and 11 of the front and rear sets of planes, and 90 is also connected by a branch cord 19 with the corresponding arm of the intermediate set of planes. By this construction and arrangement of the controlling connection, the planes may be turned from a vertical to a 100 horizontal position, and vice versa, or to any intermediate position in a ready and convenient manner.

For the purpose of driving and lifting the machine, propellers 20, preferably two 105 in number, are employed, which propellers are arranged one in rear of the other in the central line of the machine and intermediate the sets of aeroplanes. Each propeller is mounted upon a shaft 21 journaled in a 110
